Primary Examiner — Llorellys Martinez*Assistant Examiner* — Nicole M. Leech(74) *Attorney, Agent, or Firm* — Dunlap Bennett & Ludwig, PLLC; Anna L. Kinney(57) **CLAIM**

The ornamental design for a floating gem foot accessory, as shown and described.

DESCRIPTION

FIG. 1 is a top front perspective view of a floating gem foot accessory showing my new design;

FIG. 2 is a top rear perspective view thereof;

FIG. 3 is a front elevation view thereof;

FIG. 4 is a rear elevation view thereof;

FIG. 5 is a right side elevation view thereof, with the left side elevation view being a mirror image thereof;

FIG. 6 is a top plan view thereof;

FIG. 7 is a bottom plan view thereof; and,

FIG. 8 is a front perspective view thereof, shown in use. The broken lines in FIG. 8 represent environmental structure only and form no part of the claimed design. The floating gem foot accessory is shown with symbolic breaks in its length. The appearance of any portion of the floating gem foot accessory between the break lines forms no part of the claimed design.
